CLAIM

The ornamental design for a display screen or portion thereof with graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

Display screen or portion thereof with graphical user interface

1.0 is a front view.

The broken line showing of the text is for the purpose of illustrating portions of the article and forms no part of the claimed design. The outermost solid line rectangle shows a display screen or portion thereof which forms part of the claimed design.

**1 Claim, 1 Drawing Sheet
(1 of 1 Drawing Sheet(s) Filed in Color)**
